UNITED STATES PATENT OFFICE.

ZOE ARMSTRONG, OF MCPHERSON, KANSAS.

DESIGN FOR A POISON-BOTTLE.

46,719.

Specification for Design.

Patented Dec. 8, 1914.

Application filed September 9, 1913. Serial No. 788,960. Term of patent 14 years.

To all whom it may concern:

Be it known that I, ZOE ARMSTRONG, a citizen of the United States, residing at McPherson, in the county of McPherson and State of Kansas, have invented a new, original, and ornamental Design for Poison-Bottles, of which the following is a specification, reference being had to the accompanying drawing, forming part thereof.

The figure is a perspective view of a poison bottle, illustrating my design.

I claim:

The ornamental design for a poison bottle, as shown.

ZOE ARMSTRONG.

Witnesses:

HAZEL GILPIN,

AGNES McDONALD.
